CLAIM

The ornamental design for a semiconductor module for power conversion, as shown and described.

DESCRIPTION

FIG. 1 is a front view of a semiconductor module for power conversion showing my new design.

FIG. 2 is a rear view of the semiconductor module for power conversion of FIG. 1.

FIG. 3 is a top plan view of the semiconductor module for power conversion of FIG. 1.

FIG. 4 is a bottom plan view of the semiconductor module for power conversion of FIG. 1.

FIG. 5 is a right side view of the semiconductor module for power conversion of FIG. 1.

FIG. 6 is a left side view of the semiconductor module for power conversion of FIG. 1; and,

FIG. 7 is a perspective view of the semiconductor module for power conversion of FIG. 1.

The dashed-dot-dashed lines represent the boundary lines of the claimed design. The even dashed lines represent unclaimed environment that form no part of the claimed design.
